(57) **CLAIM**

I claim the ornamental design for a head worn LED array holder, as shown and described.

DESCRIPTION

FIG. 1 is a front elevation view of the head worn LED array holder showing my novel design;

FIG. 2 is a rear elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines shown in FIG. 7 are an illustration of a typical LED array and form no part of the claimed design.
